UNITED STATES PATENT OFFICE.

JACOB HARPS, OF SAN FERNANDO, CALIFORNIA.

HAND-TRUCK.

SPECIFICATION forming part of Letters Patent No. 427,232, dated May 6, 1890.

Application filed October 12, 1889. Serial No. 326,862. (No model.)

To all whom it may concern:

Be it known that I, JACOB HARPS, a citizen of the United States, residing at San Fernando, in the county of Los Angeles and State 5 of California, have invented a new and useful Automatic Hand-Truck, of which the following is a specification.

The purpose of my invention is to secure greater ease and convenience in handling 10 boxes and packages with hand-trucks. When boxes are piled one upon another and when they are placed side by side close to each other, it is quite difficult to handle them.

My invention is designed to enable the operator unaided to pick up any box exposed 15 and remove it from its position and transport it and place it where desired without handling it with the hands and without moving the boxes standing beside it.

20 The accompanying drawings illustrate my invention.

Figure 1 is a longitudinal section of my improved truck in position to load a pile of boxes. $\alpha\alpha$, Fig. 2, indicate the line of section. Fig. 2 25 is a cross-section of the truck, yy , Fig. 1, indicating the line of section. The grapple is shown in this view as it would appear if slipped down below the line of section yy . Fig. 3 is a perspective view of the hand-grapple. Fig. 30 4 is a mid-section detail of the spring which operates the ratchet-bar I. Fig. 5 is a view of an auxiliary ledge-frame adapted for attachment to the truck when it is desired to handle sacks.

35 The top or front face of the front or loading end of the truck is plain—that is to say, the truck is devoid of the ledge usually provided to project forward from the front loading end of hand-trucks to receive and support the packages. The loading end of this

40 truck is beveled on the under side to a wedge-point, as at B, and the wheels C are set with their peripheries wholly to the rear of such point, so that when the handles A are raised 45 to a vertical position, as shown in Fig. 1, the wheels will be raised clear of the ground and the truck will rest upon the wedge-points B of the handles, which form a fulcrum for the support of the truck while loading. The 50 wheels are set well back from the fulcrum-points B, so that the handles must be thrown back at an angle of about forty-five degrees

before the wheel C will touch the ground and begin to support the load. By this contrivance above described I am enabled to easily 55 place the face of the truck against the face of the box or package to be loaded, so that when the package is grappled and secured to the truck the rearward movement of the handles will cause the box or package to tilt back 60 easily until the wheels strike the ground, at which time the box or package will have been overbalanced, so as to rest upon the handles. The wheels will then form the fulcrum, and a further backward movement will raise the 65 package from the ground. It is obvious various devices may be employed to grapple the package and secure it to the truck.

The means I deem most preferable are illustrated in the drawings. 70

I fulcrum a bent lever D to the frame of the truck by means of rod E, passing through the handles from side to side. The two front ends of the lever are pointed and conveyed upward and upward in front of the face of the truck by the depressions of the rear portion of such lever, which is provided with a foot-piece G. A spring H engages with each arm of the lever to hold the rear thereof in its elevated 75 position when free, and a ratchet-bar I is provided to engage with the lever behind the spring H to hold the lever in its depressed position, as shown in Fig. 1. The ratchet-bar I preferably engages with the foot-plate G, so 80 that it can readily be released by the toe of the foot which depresses the lever. The bar is hinged to the central beam J of the frame of the truck and is held by a spring K in an extended position to engage with the foot- 85 piece G. 90

The central beam J of the truck-frame is faced with an iron strap L, the edges of which jut beyond the side of the beam to form a longitudinal guideway for the slide M of the 95 top or handle clutch, which is adapted to slide up and down along the front of the truck to engage packages of different heights. The edges of the slide M are bent to project around the jutting edges of the strap L, which fits 100 into the longitudinal channels mm , formed by bending such edges over to engage the rear side of the guide L, so that when the slide M is tilted to bring its axis oblique to the axis

of the guideway the end walls of the channels *m m* will engage the guide *L* on opposite sides, thereby clutching the same. The clutch illustrated in Fig. 3 is specially adapted for this purpose, though it is obvious other clutches may be devised to operate in combination with the truck-frame, as hereinbefore described.

N is a bent claw having its rear end pivoted to the handle-lever *O*, which is pivoted at its lower end to the lower end of the slide or frame piece *M*. Upon each side of the clutch a tie *P* is pivoted by one end to the claw at the upper arch of the bend of the claw and is pivoted at the other end to the slide *M*. A portion *Q* of the upper face of the claw is notched for engagement with the pawl *R*, which is pivoted to the handle *O* above the claw *N*. A spring-actuated trip-rod *S* is secured to the handle-lever *O* to engage with the top of pawl *R* behind its pivot, so that when the rod is depressed it will raise the pawl and allow the claw to be raised.

The auxiliary ledge-frame shown in Fig. 6 consists of a ledge *T*, having an attaching-arm *U* secured to each end on the upper side thereof. Curved lugs *V V* project backward and downward from each of these arms to enter sockets *W* in the front side of the handles. These sockets are indicated by dotted lines, Fig. 1. Perforated lugs *b* are provided to receive pins or screws, which may be passed therethrough into the handles to secure the frame to the handles.

35 The operation of the truck is as follows: The operator grasps the handles *A* in the ordinary manner and wheels the truck forward until the end *B* touches the package. The handles are then elevated, keeping the points *B* close against the package until the points rest upon the floor and the wheels are raised wholly from the floor. Then the operator grasps handle *O*, and, placing his foot upon the foot-plate *G*, simultaneously draws the handle back and forces the end of the lever *D* down. The points *X* are forced forward and upward into the rear side of the package, and at the same time the claw *N* of the hand-clutch is forced downward and backward into the top 50 of the package. The operation of the several parts of the clutch is such as to give a positive downward and backward movement to the claw whenever the handle *O* is drawn back—that is to say, the backward movement 55 of the upper end of lever *O* elevates and also retracts pivot *Y* of the claw. The rigid arm *P* prevents pivot-point *Z* from being drawn backward, except with a downward movement on the arc of a circle. Thus the rear end of *N* is given an upward and backward movement, while the front end is given a downward and backward movement very effective in clutching the package and clamping it to the truck. The pawl *R* engages with the serrated face *Q* 65 and prevents the claw from being raised or its end bounced out of the package. The strain upon the slide *M* is such as to cause it to cramp

the guide-strap *L*, so as to make the clutch stationary—that is to say, when handle *O* is drawn back its lower pivot *d* forces the bottom 70 of slide *M* backward against the guide-strap *L*, and at the same time the claw *N* is drawn back by pivot *Y*, thus forcing tie *P* back, thereby forcing back the upper end of the slide *M*, to which such tie is pivoted. This 75 simultaneous forward movement of the lower end of *M* and backward movement of the upper end of *M* causes *M* to cramp the guide-strap *L* and thereby be held stationary until the pawl is released. When a box is thus 80 clutched, it is held securely clamped to the truck, and a single box can be effectively handled without the aid of the foot-lever. For example, if the hand-clamp shown in Fig. 1 were drawn back and the top box *e* clutched 85 thereby and the truck were then tilted back, (the lever *D* being released,) box *e* would be carried off by the truck and would remain suspended until the clutch were released. When the lever *D* and the clutch are operated simultaneously, they act against each 90 other and thereby grip the package or pile of packages firmly between them. It is obvious the hand-clutch need not be movable in order to give it utility, and the frame-piece *M* might 95 be apart, the frame of the truck being fixed at a certain height if it is proposed to handle packages of a uniform height.

Now, having described my invention, what I claim as new, and desire to secure by Letters 100 Patent, is—

1. The combination of a hand-truck devoid of any loading-ledge, the pivoted foot-lever having its front end pointed and curved upward, and means for engaging the top of the 105 package.

2. The combination, with a hand-truck devoid of the ordinary loading-ledge and provided with a longitudinal guide for a clutching device, of a slide adapted to engage with 110 such guide, the handle-lever pivoted at one end to one end of such slide, the pawl pivoted to the handle, the bent claw pivoted at one end to the handle and having its upper 115 face notched for engagement with the pawl, and the tie pivoted by one end to the claw and pivoted at the other end to the slide.

3. The combination of the guideway *L*, the slide *M*, having channels *m m*, handle *O*, pivoted to the lower end of the guide, the pawl pivoted to the handle, the bent claw *N*, pivoted at one end to the handle and notched on 120 its upper face to engage with the pawl, the tie pivoted at one end to the claw and pivoted at the other end to the slide, and the 125 rod *S*.

4. The combination, with a hand-truck such as set forth, of the removable ledge-frame comprising ledge *T*, attaching-arms *U U*, and means for securing the ledge to the truck. 130

5. The combination of the hand-truck provided with means for engaging the top of the package to be handled, the pivoted spring-actuated foot-lever having upward - curved

points X, and the ratchet-bar arranged to engage with such foot-lever.

6. In a hand-truck such as set forth, the combination of the pivoted foot-lever D, having foot-piece G and upwardly-projecting points X, the frame of the truck, the ratchet-bar I, pivoted thereto, the spring K, engaging with such ratchet-bar, and the springs H, engaging with the bent lever.

7. The combination of a frame, a handle pivoted thereto, the bent claw pivoted to such handle, the tie pivoted to the bent lever and to the frame, and the pawl pivoted to the handle to engage with the claw.

JACOB HARPS.
